UNITED STATES PATENT OFFICE.

RALPH B. VESSEY AND ALBERT SCHMIDT, OF FLINT, MICHIGAN, ASSIGNEES TO CHAMPION IGNITION COMPANY, OF FLINT, MICHIGAN, A CORPORATION OF MICHIGAN.

ELECTRIC TERMINAL.

1,391,810.

Specification of Letters Patent. Patented Sept. 27, 1921.

Application filed January 17, 1919. Serial No. 271,624.

To whom it may concern:

Be it known that we, RALPH B. VESSEY and ALBERT SCHMIDT, both citizens of the United States of America, residing at Flint, in the county of Genesee and State of Michigan, have invented certain new and useful Improvements in Electric Terminals, of which the following is a specification, reference being had therein to the accompanying drawings.

The invention relates to electric terminals designed for engagement with connectors and having particular reference to constructions adapted for use on spark plugs.

15 It is the object of the invention to obtain a simple construction which may be used with several different types of connectors, as hereinafter set forth.

In the drawings:

20 Figure 1 is an elevation of the terminal as applied to a spark plug;

Fig. 2 is a vertical central section therethrough.

25 Fig. 3 is a similar view showing an eye terminal in engagement therewith.

In the present state of the art it is usual to provide spark plugs with terminals formed by a threaded stud or extension of the insulated electrode and a clamping nut 30 engaging said stud. Various types of connectors have been used in connection with

the plugs, the chief of which are, first, an eye member for engaging the stud which is clamped by the nut; second, a spring socket

35 contact for engaging a stud bearing on the nut; and third, a slotted contact member which is insertible in a narrow groove in the terminal. To provide for the latter construction, it is usual to form the nuts with

40 narrow grooves therein having no other function than for engaging this type of terminal. Where the nuts are formed of soft metal, such grooves may be readily machined therein, but for other types of

45 nuts, and particularly where formed of pressed sheet-metal, it is difficult to provide such a groove. The present invention overcomes the difficulty by forming a narrow

groove between a portion of the threaded

50 stud and the lower face of the nut, this being accomplished by a shoulder on the stud, slightly spaced from the bearing for the connector. Thus the nut when screwed down upon the stud will be held spaced from

the bearing, but at the same time an eye 55 type of connector, which is always of greater thickness than the slot, will be clamped against the bearing on the stud by the nut.

In detail, A is the terminal or electrode 60 extending outward from the insulator B of a spark plug. C is a collar portion of enlarged diameter on the terminal A which forms on its outer face a bearing D for the connector. Extending outward beyond this 65 collar C is the threaded stud E with which a clamping nut, such as F, may be engaged.

To form the groove for engaging the slotted terminal the stud E is shouldered at G a slight distance above the bearing D so that 70 the nut when screwed inward will be limited in its movement by said shoulder G. This will leave a narrow groove H between the nut and the bearing D which will receive the slotted terminal. To form the 75 shoulder G, the portion of the stud I below the same is of slightly greater diameter, but the dimension is limited so that it will receive an eye connector such as J, permitting the latter to rest upon the bearing D; the 80 connector J being of greater thickness than the distance between the shoulder G and bearing D the nut F will exert a clamping pressure thereon.

As shown in Fig. 2, the nut F is formed 85 of a hollow pressed sheet-metal member which is fashioned to form a headed hollow stud K and a cylindrical portion L of larger diameter. Within the latter portion is a disk member M which is centrally apertured and threaded for engaging with the stud E. This type of nut is not essential to the present invention, but inasmuch as it would be difficult to form the narrow groove in the pressed sheet metal, the shouldered 90 stud is particularly advantageous when used in connection therewith.

Although I have shown and described the nut or cap member the same is covered by my copending application entitled Electric terminal fitting, Serial No. 271,623, filed January 17, 1919.

What we claim as our invention is:

1. An electric terminal, comprising a threaded stud member, a laterally-extending 105 bearing portion on said stud member for engagement with a connector, a clamping nut engaging the threaded stud, and means for

- holding said nut spaced from said bearing to form a narrow groove.
2. An electric terminal, comprising a threaded stud, a laterally-extending bearing on said stud forming a seat for a connector, a nut engaging the threaded stud, and a shoulder forming a stop for said nut holding the same spaced from said bearing to form a narrow groove therebetween.
- 10 3. An electric terminal, comprising a threaded stud, a laterally-extending collar on said stud for receiving a connector, a nut engaging the threaded stud, and a portion of said stud of slightly greater diameter than the threaded portion forming a shoulder limiting the inward movement of the nut to

form a narrow groove between the same and said bearing.

4. An electric terminal, comprising an insulated threaded stud, an annular collar on said stud forming a seat for a connector, a nut engaging the threaded stud for exerting a clamping pressure upon an eye connector when seated on said bearing, and a shoulder on said stud spaced from said bearing by less than the thickness of said eye connector for limiting the inward movement of said nut to form a narrow groove.

In testimony whereof we affix our signatures.

RALPH B. VESSEY.
ALBERT SCHMIDT.
